[57] **CLAIM**

The ornamental design for a bracket for attaching a nozzle and light, as shown and described.

DESCRIPTION

FIG. 1 is a front elevational view of a bracket for attaching a nozzle and a light showing my new design, the rear being a mirror image;

FIG. 2 is a right side elevational view thereof; FIG. 3 is a top plan view thereof with bottom view being identical; and

FIG. 4 is a left side elevational view thereof, the light and nozzle being shown in broken lines for illustrative purposes only.

FIG. 1.

FIG. 2.

FIG. 3.

FIG. 4.
